Primary Examiner — Andrew Kerr(74) *Attorney, Agent, or Firm* — Bochner IP, PLLC; Andrew D. Bochner(57) **CLAIM**

The ornamental design for a decanter, as shown and described.

DESCRIPTION

FIG. 1 is a top, front, right-side perspective view of a decanter;

FIG. 2 is a front elevation view thereof, the rear elevation view being a mirror image;

FIG. 3 is a left-side elevation view thereof;

FIG. 4 is a right-side elevation view thereof;

FIG. 5 is a top plan view thereof;

FIG. 6 is a bottom plan view thereof; and,

FIG. 7 is a cross-section view thereof, taken along line 7-7 of FIG. 3.

The broken lines in the drawings depict portions of the decanter that form no part of the claimed design.

1 Claim, 5 Drawing Sheets(56)
